UNITED STATES PATENT OFFICE.

ALONZO D. HOBBIE, OF BERGEN POINT, NEW JERSEY.

FOLDING OR KNOCKDOWN CRATE.

SPECIFICATION forming part of Letters Patent No. 398,727, dated February 26, 1889.

Application filed August 2, 1888. Serial No. 281,725. (No model.)

To all whom it may concern:

Be it known that I, ALONZO D. HOBBIE, a citizen of the United States, residing at Bergen Point, in the county of Hudson and State 5 of New Jersey, have invented certain new and useful Improvements in Folding or Knockdown Crates, of which the following is a full, clear, and exact description.

My invention relates to an improvement in 10 knockdown or folding crates, by which is understood crates, boxes, or the like, which are capable of being reduced in their cubic measurement for the purpose of reducing their bulk and consequent expense in shipment, &c. For 15 a similar purpose crates have been constructed so as to permit the complete separation of the parts, as well as such a disposition of several parts as to permit their being folded together, so as to allow the sides, top, and bottom to be 20 folded inwardly. While such constructions are found in many respects to be efficacious, there is a decided objection in the matter of economy, and it is to overcome this objection that my invention is particularly directed, al- 25 though a further purpose of my invention is to produce a crate of this nature which shall possess the largest amount of strength and durability, combined with a capacity for being readily folded and set up.

30 To this end my invention consists, substantially, in the details of construction and combination of parts, hereinafter more clearly pointed out and claimed.

In the drawings, Figure 1 represents my 35 improved crate folded ready for shipment empty. Fig. 2 is a perspective view showing my improved crate open, but without the side and end pieces. Fig. 3 is a vertical cross-section viewed in the direction of the arrow x , Fig. 2. Fig. 4 is a vertical cross-section viewed 40 in the direction of the arrow y , Fig. 2. Fig. 5 is a broken perspective view of a crate with one side and one end piece applied; and Figs. 6 and 7, a view in elevation and cross-section, 45 respectively, of one of the side pieces.

While the drawings illustrate my invention as having solid sides, ends, top, and bottom, it will be clear that these may be slatted instead without departing from the invention.

50 A is the frame-work of the top of the crate, and B is the frame-work of the bottom. To the frame-work A is secured by hinges t the

permanent cover C, which may also be provided with the spring-catch l' , to engage the pin t' on the frame-work in the common manner. It 55 may be desirable to apply braces to the under side of the top, as shown in Fig. 2, to confer additional strength. The frame-work B has secured to it the permanent bottom D, which may be nailed or otherwise secured thereto. 60 The end pieces, A', of the top frame, A, are provided with longitudinal slots s , leading from near the outer corners to near the middle of the end pieces, as shown, and the end pieces, B', of the bottom frame, B, are pro- 65 vided with similar slots, r . Cross-arms forming braces E are pivoted at their center q , and their ends are caused to engage in the slots r by means of pins provided with buttons p . It will thus be seen that by spreading the arms E the frames A and B may be drawn together until the lugs on the pivoted arms reach the outermost limits of the slots s and r , respectively, when the frames will 70 come together, while an opposite motion of 75 the pivoted levers will separate the frames, and by reason of the nearly perpendicular line assumed by the arms E when the lugs p are at the innermost ends of the slots s and r , respectively, a firm brace is provided to maintain the upper and lower frames at the proper 80 distance from each other. The lower frame may also be provided with the spring-catch o , to engage the pin o' on the upper frame and serve to keep the frames in contact when the 85 crate is closed. A similar spring catch and lug may be provided on the interior of the forward part of the frame, if desired. Additional strength may be obtained by providing the cross-braces n on the bottom and corner- 90 braces m , as shown in Fig. 2. A desirable feature of these corner-braces is that they project above the top of the lower frame, B, and serve as strengtheners of the upper frame, A, when the crate is folded, as well as supports 95 and braces for the sides and end pieces when set up. Braces n' may be provided on the outside on either or both of the upper and lower frames, which, besides serving to strengthen the frame, provides a guard for 100 the buttons p .

The sides and end pieces of the box or crate may be in the form of separate pieces entirely detachable from the frames. In this case they

are provided with indentations l'' on their exterior, to enable them to engage with the pins l , provided on the interior of the side and end pieces of the frames A and B. When thus 5 constructed, the end and side pieces are withdrawn from the frame and laid one on another on the bottom when the crate is folded. These side and end pieces are engaged with the pins by inserting at an angle of about forty- 10 five degrees their lower ends behind the braces n , so that the pins may enter the indentations or openings l'' , and thereafter said side and end pieces are raised upright into position.

15 To operate the crate when in the folded position shown in Fig. 1, the lid is raised and the cross-arms E are brought toward a vertical position, separating the frames. Thereupon the side and end pieces are applied so 20 that the indentations therein will engage the lugs l , and the device is then set up ready for use for transporting berries or other contents. When empty, the side and end pieces are removed and laid or folded in the bottom or top, 25 and the pivoted arms E are separated so as to approach a horizontal position, bringing the upper and lower frames together until the spring-catches o engage the pins o' , when the crate occupies the smallest possible cubic 30 space.

What I claim as new, and desire to secure by Letters Patent, is—

1. A folding crate comprising separate upper and lower frames held together by pivoted braces engaging slots in the frames, side and 35 end pieces having indentations, and pins on the inner side of the top and bottom frames to engage the indentations in the side and end pieces, substantially as described.

2. A folding crate comprising top and bottom frames, A and B, pivoted braces E, engaging slots in the top and bottom frames, folding side and end pieces, and spring-catch o on one frame and pin o' on the other frame, 40 whereby when the crate is folded the frames 45 will be kept together, substantially as described.

3. A folding crate or box comprising separate upper and lower frames having slots in their opposite ends, cross-braces centrally pivoted to each other and engaging at their ends the slots in the frames and serving, when in their extended or vertical position, to maintain the frames apart, corner-braces m on one frame, and folding side and end pieces provided with indentations adapted to engage with projections on the upper and lower frames, as set forth.

In testimony whereof I have hereunto set my hand this 10th day of July, A. D. 1888.

ALONZO D. HOBBIE.
